ADOLPH HAUSSKE, OF CHICAGO, ILLINOIS.

DESIGN FOR A SOFA.

Design No. 16,248, dated September 15, 1885.

UNITED STATES PATENT OFFICE.

ADOLPH HAUSSKE, OF CHICAGO, ILLINOIS.

DESIGN FOR A SOFA.

SPECIFICATION forming part of Design No. 16,248, dated September 15, 1885.

Application filed May 28, 1884. Term of patent 34 years.

To all whom it may concern:

Be it known that I, ADOLPH HAUSSKE, a citizen of the United States, residing at Chicago, in the county of Cook and State of Illinois, have invented and produced a new and original Design for Sofas, of which the following is a specification, reference being had to the accompanying drawing, forming a part thereof, in which is shown the front elevation 1c of a sofa illustrating my design.

The leading feature of my design is a top panel or bar having mounted thereon and projecting above its upper edge an extension having a depressed or struck-up scalloped surface, the outline of which is within the upper and lower edge of the extension.

The other leading features of my design consist in a raised or depressed surface in the central and broad panel of the back, and representing an urn with scroll-work extending from and above the top of the urn and representing a configuration approximating foliage.

A is the top bar of a sofa, above which is an extension, B, projecting above it, of a length 25 shorter and of a width somewhat greater than that of the bar.

Just above the juncture of the extension of the bar are two parallel lines, *a*, in the extension, the upper edge of the extension being 30 somewhat convexed, as shown at *b*, and between this convexed portion and the parallel lines is a cove having a scalloped surface somewhat resembling a series of leaves or blades, *c*, arranged side by side of each other. 35 This cove does not extend quite the length of the extension, the ends of which terminate in knobs or heads *d d*.

Near each side edge of the bar *a* are two parallel lines, *e e*, which extend the length of 40 the bar, and so much of the surface of the bar as lies between these lines and immediately below the extension is a plain surface, *f*, beyond each end of which, and extending to the respective extremities of the bar and between

the opposing parallel lines, is an indented surface. 45

The central and broad panel, C, has extending lengthwise of it a raised or indented surface representing an urn, D, of an angular form, and projecting from and above the top 50 of this urn is a raised or indented scroll surface, E, having more or less likeness to foliage.

The background of the panel on which the urn and foliage are shown is plain, and the longitudinal edges of the panel are bounded by 55 parallel lines or bead-work *g*.

What I claim, and desire to secure by Letters Patent, is—

1. The design for sofas herein shown and described, the same consisting of a top bar, an 60 extension of shorter length rising above said top bar, and provided with a cove extending lengthwise of its face, the end of said cove and the end of the extension terminating in knobs or heads. 65

2. In a design for a sofa herein described and shown, the central panel provided with an urn raised or depressed on the central panel and extending lengthwise of said panel of the back.

3. The design for a sofa herein shown and described, the same consisting of an urn on the central panel of the back, and the foliage or scroll-like work extending from and above the top of the urn. 70

4. The design for a sofa, the same consisting of the urn on the panel of the back, a foliage extending from and above the urn, and on said panel a plain surface on and the width of the top bar, and extending at a right angle 80 to the length of the urn, a cove in an extension above a top bar, and the leaves or blades arranged side by side in said cove. 75

ADOLPH HAUSSKE.
